UNITED STATES PATENT OFFICE

EDWARD H. REMDE, OF CLEVELAND, OHIO, ASSIGNOR TO THE BAKER-RAULANG COMPANY, OF CLEVELAND, OHIO, A CORPORATION OF OHIO

CRANE

Original application filed June 22, 1925, Serial No. 38,647. Divided and this application filed October 3, 1925. Serial No. 60,357.

This invention relates to a crane mounted on wheels certain of which are driven, whereby it may be operated for effecting certain operations or moved from place to place.

5 This application is a division of my original application filed June 22, 1925, Serial No. 38,647.

10 One object of the invention is to provide the boom with an extension member adapted to engage loads and elevate them to and from positions beyond the reach of the lifting element suspended from the free end of the boom.

15 Another object of the invention is to construct a boom for a crane with an extension member and to provide the boom with supporting elements adapted to engage and removably support the extension member either in an operative position or in an inoperative position.

20 Other objects of the invention will be apparent to those skilled in the art to which my invention relates from the following description taken in connection with the accompanying drawing, wherein

25 Fig. 1 is a side elevation of a crane embodying my invention.

Fig. 1^a is a fragmentary side view showing the extension member supported in operative position.

Fig. 2 is a fragmentary plan view of the main boom showing the extension member mounted thereon in its inoperative position.

30 Fig. 3 is a section on the line 3—3 of Fig. 2.

Fig. 4 is a section on the line 4—4 of Fig. 1.

Fig. 5 is a section on the line 5—5 of Fig. 1.

In the drawings, 1 indicates a frame of any desired shape and form, preferably comprising a main portion 1^a on which the mechanisms for raising and lowering loads and moving the load carrying member, to be later referred to, are supported, and a platform portion 1^b, on which loads may be placed. 2, 3, indicate the supporting wheels for the frame.

4 indicates a motor arranged to drive the wheels 3 through a suitable transmission mechanism in a housing 4.

50 The traction wheels 3 are pivoted on the housing members 4 in a well known manner

so that the wheels may be driven while being steered.

8 indicates the axle for the trailing wheels 2, having at its opposite ends suitable knuckles, which serve as pivotal supports for the wheels 2, whereby they may be steered. 9 indicates connections between and operatively connected to the wheels 2, 3, for steering them simultaneously. 11 indicates a support on which the operative stands while operating the truck.

15 indicates a dash on which are mounted certain of the controlling or operating elements for the truck and the load supporting and engaging members. 16 indicates a foot pedal associated with the platform 11, and arranged to control the release and application of a brake mechanism, indicated as an entirety at 17, preferably constructed to normally act on an element driven directly by the motor. 23 indicates as an entirety a controller for cutting in or closing the circuit to the motor 4, preferably operated by a lever 27.

33 indicates a vertically arranged axle or pivot member on the frame portion 1^a forming a shaft for a frame 34. The frame 34 forms a base for a battery or batteries 36.

40 indicates as an entirety the boom pivoted on the inner end of the frame 34. 41 indicates a motor supplied by current from the batteries 36 and operating through a power transmitting mechanism to drive two winding drums, one for the flexible member 40' which is connected to the boom 40 and operates to swing it in vertical planes and the other for the flexible member 57 which is connected to the load engaging member 55, suspended from the outer end of the boom 40. 47 indicates a gear fixed to the frame 34 in concentric relation to the shaft 33 and engaged by a driven pinion 49^a whereby it is rotated from the position shown in Fig. 1 in either direction to effect slewing of the boom 40. For this purpose, the pinion 49^a is driven by a motor 49.

The boom 40 preferably comprises a pair of spaced channel members 40^a connected by bars 40^b, 40^c, which may be curved forwardly and downwardly at their upper ends. The

channel members are mounted at their lower ends on a pivot pin 52 carried by the frame 34.

The load engaging member 55 preferably comprises a hook depending from a casing 56, which in turn is supported or suspended by the cable or other flexible connection 57.

As will be understood, the cable winding drums are rotated independently of each other to swing the boom 40 and raise or lower

10 the member 55; the cable 40' being reeved around sheaves, certain of which are shown at 60, 61, and connected to a link 65 pivoted on the rod 39^b and the cable 57 being reeved around sheaves 69, 70, mounted on the adjacent upright 37 and pin 52, respectively, and sheaves 71, 72, mounted on the boom 40. The sheave 71 is carried by a shaft 63^a supported by the plates 53 and the sheave 72 is supported by a cross shaft 72^a.

20 170 indicates an auxiliary boom adapted to be detachably and pivotally connected at its inner end to the boom 40 and supported at or near its outer end by the load engaging element 55 which detachably engages therewith.

25 The auxiliary boom 170 may be of any desired length and is preferably formed from a pair of channel bars secured together back to back in any desired manner. The connection of the auxiliary boom 170 with the main boom 30 40 is preferably of the universal joint type. Near the outer end of the auxiliary boom I provide an upstanding plate 178. The plate 178 is formed with one or more openings 179, in which the hook 55 is inserted to support 35 the outer end of the boom 170. The plate 178 is preferably clamped between the channel bars constituting the auxiliary boom. 180 indicates a load engaging device suspended from the auxiliary boom, preferably near its 40 free end. This device may be of any desired form, depending upon the shape and nature of the load that is to be engaged, but it is herein illustrated as a hook having a swiveled shank connected by links to a cross bar sup-

45 ported in openings formed in the bars of the auxiliary boom 170. The device 180 may be used to detachably connect the free end of the boom 170 to the main boom 40, as shown in dotted lines in Fig. 1, to hold it in an inoper-

50 ative position when not in use or when the loading engaging member 55 is being used to handle loads. When the boom 170 is moved into such position, the hook 180 may engage a cross pin 40^c. The auxiliary boom 170 may

55 be detached by removing the hook 55 from the opening 179 and removing either of the pins, 172, 175, the latter being preferably held in position by cotter pins and the former being held in position by nuts 182. When the

60 auxiliary boom 170 is removed or positioned in its inoperative position, the main boom 40 and the load engaging member 55 are capable of being operated in the usual manner to raise and lower loads to and from varying positions

65 at either side of the truck frame 1. When the

auxiliary boom 170 is assembled as shown in Fig. 1, the crane may be utilized to perform various load handling operations, for example, in making machine assemblies. The auxiliary boom 170 may be operated to lift a part, unit or element and support it while being moved to the place of assembly and there held in position while assembly is effected. By reason of the fact that the hoist mechanism is utilized to support the outer end of the auxiliary boom and its inner end has universal joint connection with the main boom 40, it will be seen that the load can be adjusted up or down and laterally to facilitate its positioning for connection with or in the machine being assembled. Furthermore by swinging the main boom 40 up or down, adjustment of the load in an endwise direction can also be made. As the boom 170 extends laterally in a substantially horizontal direction, it can be used to support and position parts, units and elements below or underneath a frame or structural part.

183 indicates an extension member adapted to be removably supported on the free end of the main boom 40 and support parts, units and elements for assembly purposes in or at relatively high elevations or to lift them to such position; or to engage the same for disassembly or lowering. 185 indicates a hook swiveled on a suitable device which in turn is suspended by a link from the free end of the extension member. When these parts, units and elements are engaged, they may be lifted to and from positions beyond the range of the load engaging member 55. In such operations the load is raised to an intermediate position by the member 55; then the boom and truck frame are manipulated to (1) engage the hook 185 with the load and (2) then lift the load to the elevated position desired. In making disassemblies from positions beyond the range of the load engaging member 55, the extension member, boom and truck frame are manipulated in the reverse directions. The extension member 183 preferably comprises a tubular bar adapted to extend through an opening 184 formed in the upper plate 40^b and removably fit a socket 185^a, rigidly supported between the boom bars 40^a near their free ends, being held therein by a pin 183^a. The socket comprises a U-shaped plate 185^{a'}, connected at its ends to a cross member 185^b, which is secured to the bars 40^a as shown in Fig. 5. The extension member 183 extends endwise from the main boom 40 and carries at its outer end the depending hook or other device 185 by means of which it may engage and support a load.

When removed from the socket 185^a, the extension member 183 may be removably secured to the boom 40, preferably by means of a socket 186 into which its inner end fits and a clamping block 187 carried by one of the bars 40^a, the block 187 being provided

with a hinged plate 187^a which engages the extension member to hold it on the block 187. The plate 187^a is secured in clamping position by a suitable device 187^b. As the extension member 183 is rigidly carried by the boom 40 and extends from the free end thereof, operation of the boom 40 will swing the outer end of the extension member to move its suspension hook 185 or the load carried thereby as desired.

From the foregoing description it will be seen that I have provided a crane which is capable of effecting lifting and lowering operations at relatively great heights and under varying conditions by the provision of an extension member which can be assembled in position in a ready manner for engaging the loads to be lifted to or from such positions and that such member can be removed at will to facilitate the operation of the boom and also movement of the crane into and out of structures or below overhanging walls in a ready manner.

To those skilled in the art to which my invention relates many alterations in construction and widely differing embodiments and applications of the invention will suggest themselves without departing from the spirit and scope thereof. The disclosures and the description herein are purely illustrative and are not intended to be in any sense limiting.

What I claim is:

1. In apparatus of the class described, the combination of a wheel supported frame, a boom swingably supported on the frame, a hoist mechanism having a load engaging member suspended from the free end of said boom, means for swinging said boom upwardly and downwardly, an extension member removably mounted on and extending from the free end of said boom, and supporting elements on said boom arranged to removably engage said extension member when removed from its operative position.

2. In apparatus of the class described, the combination with a wheel supported frame, of a boom swingably mounted thereon, means for swinging said boom, a hoisting mechanism including a load engaging member suspended from said boom, an extension member detachably supported on the free end of said boom, and separate means carried by said boom for detachably supporting said member when detached from said boom.

3. In apparatus as claimed in claim 2 in which the separate supporting means for the extension member comprise a pair of devices engaging said member at spaced points, one thereof constituting a clamp.

4. In apparatus of the class described, the combination of a frame, power means thereon, a boom pivoted on said frame and connected with said power means, an extension member arranged to engage a load at its outer end, means for removably supporting the

inner end of said member on said boom with its outer end in operative position, and means for supporting said member on said boom in an inoperative position, the last said supporting means comprising a socket arranged to receive the inner end of said member and a pair of clamping means engaging said member near its opposite end.

In testimony whereof, I have hereunto affixed my signature.

EDWARD H. REMDE.
